UNITED STATES PATENT OFFICE.

CHARLES J. HURLEY, OF SHARON HILL, PENNSYLVANIA.

ELECTRICALLY-CONTROLLED TRAIN-STOPPING MECHANISM.

1,004,790.

Specification of Letters Patent.

Patented Oct. 3, 1911.

Application filed August 20, 1910. Serial No. 578,110.

To all whom it may concern:

Be it known that I, CHARLES J. HURLEY, a citizen of the United States, residing at Sharon Hill, in the county of Delaware and State of Pennsylvania, have invented certain new and useful Improvements in Electrically-Controlled Train-Stopping Mechanism, of which the following is a specification.

10 My invention relates to improvements in electrically controlled train stopping mechanism, the object of the invention being to provide improved mechanism on railway rolling stock which is electrically controlled 15 and adapted to apply the air brakes of a train entering a block already occupied or signal the engineer of the danger.

A further object is to provide improvements of this character which are designed 20 for use on railway blocks employing the normally closed electric circuit system, said circuits being opened by the entrance of a train on the block and said open circuit causing the operation of mechanism to apply the air 25 brakes or signal the engineer of the train entering the block, which mechanism, if the circuit is closed and the block not occupied, will not operate the air brakes or signal the engineer.

30 A further object is to provide improvements of this character which will operate with block signaling mechanism, and not interfere with the ordinary train signaling systems in use.

35 With these and other objects in view, the invention consists in certain novel features of construction and combinations and arrangements of parts, as will be more fully hereinafter described and pointed out in the 40 claims.

In the accompanying drawings: Figure 1, is a view partly in side elevation and partly diagrammatic illustrating my improvements. Fig. 2, is a view in elevation at 45 right angles to Fig. 1, and Fig. 3, is a top plan view.

My improvements are shown diagrammatically, and 1 is a support which is preferably a part of the locomotive, and may of 50 course be on a car or elsewhere about the rolling stock.

2, is an air brake valve, and 3 a vertically movable plunger adapted to open the valve 2 and normally held in its lowered position 55 by means of a coiled spring 4. Part 2 illustrates diagrammatically an air brake valve,

but may also represent some means for communicating a signal to the engineer in the cab, and I would have it understood that when I refer to "train controlling mechanism" I employ this language broadly to mean either brake applying means or signaling means for the engineer.

5 5, is a vertically movable plunger which is mounted to slide in brackets 6 on support 1, and is normally held in its lowest position by means of a coiled spring 7. The lower end of this plunger 5 is provided with a shoe 8 adapted to be elevated by a cam track 9, which latter is in the electric circuit with the block. It may also be an electric circuit with any ordinary block signaling system of the closed circuit type. The upper end of plunger 5 is recessed as shown at 10 to receive a trip 11, said trip pivotally connected 10 to an upwardly projecting lug 12 on plunger 5 by means of a pin 13, and the trip normally held in vertical alinement with the plunger by means of a small coiled spring 14.

15, is a bracket support for a horizontally movable pin 16, which projects into a recess 17 in trip 11, and is normally held in this position by means of a spring 18. 19 is an electro-magnet which when the shoe 8 engages the cam track 9, if the electric circuit of the block is closed, will be magnetized so as to draw a pivoted armature 20 toward the same. This armature 20 is connected by a link 21 with the pin 16, so that the pin 16 will be drawn out of the recess 17. One 20 wall of this recess 17 is in the form of a cam illustrated at 22, and the upper end of the trip 11 is beveled so that when pin 16 is in the recess 17, and plunger 5 is moved upward, the engagement of the pin against 25 the cam wall 22, will cause the trip 11 to pivot and move inwardly into the path of plunger 3, the lower end of the latter being notched as illustrated at 23 to receive the end of the trip and be moved upward thereby. When the pin 15 is drawn out of the recess 17 by the electro-magnet 19, plunger 5 will be moved upward without engaging plunger 3, hence not operating the train stopping means. It will therefore be noted 30 that if no train is on the block ahead, the normally closed circuit of the block will, when shoe 8 rides on track 9, energize the magnet 19, causing it to draw back pin 16, and allowing the plunger 5 to move up 35 without stopping the train. If, however, a train occupies the block ahead, the circuit

will be open, the magnet 19 will not be energized, the pin 16 will be in the recess 17 so as to pivot the trip 11, when plunger 5 moves upwardly causing the trip to engage 5 in the notch 23 in plunger 3, and operate the train stopping means.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. In a mechanism of the character described, the combination with a support and train controlling means thereon, of a vertically movable plunger, a pivoted trip on the plunger, a cam track, a shoe on the plunger adapted to engage the cam track, and electric means in circuit with said plunger and track, and adapted to control the movement of said trip whereby the trip may or may not operate the train controlling means, substantially as described.

2. In a mechanism of the character described, the combination with a support and train controlling means thereon, of a vertically movable plunger, a pivoted trip on the plunger, a cam track, a shoe on the plunger adapted to engage the cam track, a movable pin adapted to be engaged by said trip to cause the same to rotate on its pivot so that it will engage the train controlling means, and an electro-magnet in circuit with said plunger and track and adapted to move said pin out of engagement with the trip, substantially as described.

3. In a mechanism of the character described, the combination with a support and train controlling means on the support, of a vertically movable plunger, a shoe on the plunger, a cam track engaged by said shoe to move the plunger vertically, but out of alignment with the train controlling means, a pivoted trip on the plunger, a pin adapted to be engaged by said trip to cause the same to rotate on its pivot so that it will engage the train controlling means, and an electro-magnet for moving said pin, substantially as described.

4. In a mechanism of the character described, the combination with a support and train controlling means on the support, of a vertically movable plunger, a shoe on the plunger, a cam track engaged by said shoe

to move the plunger vertically, but out of alignment with the train controlling means, 60 a pivoted trip on the plunger, a cam recess in said trip, a bracket on the support, a sliding spring-pressed pin in said bracket projected into said cam recess of the trip to move the trip into position to engage the 65 train controlling means, and an electro-magnet for moving said pin out of said recess, substantially as described.

5. In a mechanism of the character described, the combination with a support and 70 train controlling means on the support, of a vertically movable plunger, a shoe on the plunger, a cam track engaged by said shoe to move the plunger vertically, but out of alignment with the train controlling means, 75 a pivoted trip on the plunger, a cam recess in said trip, a bracket on the support, a sliding spring-pressed pin in said bracket projected into said cam recess of the trip, an electro-magnet for moving said pin out of said recess, said train controlling means having a notch in its lower end, and the upper end of said trip beveled whereby when the trip is pivoted by the pin, it will move into the notch in the train controlling 80 means, substantially as described.

6. In a mechanism of the character described, the combination with a support and train controlling means on the support, of a vertically movable plunger, a shoe on the plunger, a cam track engaged by said shoe to move the plunger vertically, but out of alignment with the train controlling means, 85 a pivoted trip on the plunger, a cam recess in said trip, a bracket on the support, a sliding spring-pressed pin in said bracket projected into said cam recess of the trip, an electro-magnet for moving said pin out of said recess, said train controlling means having a notch in its lower end, and the upper 90 end of said trip beveled whereby when the trip is pivoted by the pin, it will move into the notch in the train controlling means, 95 substantially as described.

In testimony whereof I have signed my 100 name to this specification in the presence of two subscribing witnesses.

CHARLES J. HURLEY.
